ATTYS.

UNITED STATES PATENT OFFICE.

JOSEPH C. LEWIS, OF MASSILLON, OHIO.

SWITCH.

1,402,518.

Specification of Letters Patent. Patented Jan. 3, 1922.

Application filed October 5, 1920. Serial No. 414,753.

To all whom it may concern:

Be it known that I, JOSEPH C. LEWIS, a citizen of the United States, residing at Massillon, in the county of Stark and State of Ohio, have invented a new and useful Switch, of which the following is a specification.

This invention relates to improvements in switches and more especially to a quick action switch adapted for use in a service entrance and is a division of my copending application for Entrance switch and service box, filed Oct. 3, 1919, Serial No. 328,104.

The objects of the invention are the provision of a quick action switch for service entrance which is constructed in such a manner that it will stop only at a fully open or fully closed position and which will operate rapidly to throw from the open to the closed position or vice versa.

With these objects in view the invention consists in the novel construction and arrangement of parts, hereinafter described, illustrated in the accompanying drawings, and particularly pointed out in the appended claims, it being understood that various changes in the form, proportions, size and minor details of construction may be made within the scope of the appended claims, without departing from the spirit or sacrificing any of the advantages of the invention.

The invention thus set forth in general terms is illustrated in the accompanying drawings forming part hereof, in which— Figure 1 is a side elevation of the quick action switch showing the same in the closed position.

Fig. 2 is a longitudinal sectional view through the switch showing the same in the open position.

Fig. 3 is an end view of the switch in the opened position, a portion being broken away for purpose of illustration.

Fig. 4 is a section on the line 4—4, Fig. 1. Fig. 5 is a detail perspective view of a portion of the switch mechanism.

The line wires are attached to a pair of terminals 9 upon the block 2, to which terminals are connected the contact clips 10. The adjacent ends of the switch blades 11 are arranged to engage the contact clips 10, the other ends of said switch blades engaging the contact clips 12 which are attached to the terminals connected with the sockets 55 of the line fuses, these sockets being mounted on the insulated block 2.

The switch is of the quick action type and is contained within an inverted U-shaped frame 18 provided with the downwardly depending centrally located portions 19 upon each side. The switch blades 11 are carried upon the out-turned oppositely disposed portions 20 of the U-shaped member 21, which U-shaped member is provided with bearing portions 22 journaled in the slots 65 23 formed in the member 19. A member 24, comprising two L-shaped portions 25 connected at their upper extremities by a bar 26 is pivoted at its lower ends to the members 19 as indicated at 27, a coil spring 28 70 connecting the bar 26 with the lower portion of the U-shaped member 21.

The push rod 29 is formed of suitable insulated material and provided with a push button 30 upon its upper end, the lower end 75 of said rod being provided with a yoke 31 having bearing portions 32 journaled in suitable apertures 33 in the member 24. Stops 34 and 35 are provided upon the frame 18 being preferably punched therein, to limit 80 the movement of the U-shaped member 21 in the on and off positions of the switch respectively, the stop 34 being so shaped that it receives the end thrust of the push rod 29 in the on position of the switch. 85

I claim:

1. A switch comprising a frame, a U-shaped member provided with oppositely disposed bearing portions at its upper end journaled within the frame, switch blades 90 carried upon said bearing portions, an L-shaped member pivoted at one extremity to the lower portion of the frame, the upper end thereof arranged to normally rest at either side of the pivotal point of the U-shaped member, a spring connecting the upper end of the L-shaped member with the U-shaped member, means for limiting the movement of the U-shaped member in either direction and means for throwing the L- 95 shaped member over the pivotal point of the U-shaped member.

2. A switch comprising an inverted U-shaped frame having inwardly disposed stop portions formed at opposite ends thereof, 105 depending bearing portions provided upon opposite sides of the frame, a U-shaped member having journal portions journaled in said bearings, switch blades carried by said U-shaped member and arranged to be moved 110 into engagement with each of said stop bearings, a double L-shaped member provided

with a cross bar at its upper end, the lower end of said L-shaped member being pivoted upon the bearing members beneath the pivotal point of the U-shaped member, the cross bar thereof arranged to normally rest at either side of the pivotal point of the U-shaped member, a spring connecting said cross bar with the U-shaped member, and means connected to the L-shaped member intermediate its ends for throwing the same over the pivotal point of the U-shaped member.

3. In an apparatus of the character described, a switch comprising a frame, a U-shaped member pivoted within said frame,

switch blades carried by said U-shaped member, a member pivoted upon the frame at points beneath the pivotal points of the U-shaped member, a cross-bar upon said last named member arranged to normally rest at either side of the pivotal point of the U-shaped member, a spring connecting said cross bar with the U-shaped member, means for limiting the movement of the U-shaped member in either direction, and means for throwing said pivoted member over the pivotal point of the U-shaped member.

In testimony that I claim the above, I have hereunto subscribed my name.

JOSEPH C. LEWIS.
